[57] CLAIM

The ornamental design for a gas pump nozzle clip and key holder, as shown.

DESCRIPTION

FIG. 1 is a front elevational view of a gas pump nozzle clip and key holder showing my new design;
FIGS. 2 and 3 are, respectively, left and right side elevational views thereof;
FIG. 4 is a top plan view thereof, the bottom plan view being a mirror image thereof; and
FIG. 5 is a left side, top and front perspective view thereof.

FIG.1

FIG.2

FIG.3

FIG.4

FIG.5
